UNITED STATES PATENT OFFICE.

ALBERT L. FIERLEIN, OF BATAVIA, ILLINOIS.

SWIMMING DOLL.

1,399,855.

Specification of Letters Patent. Patented Dec. 13, 1921.

Application filed October 28, 1920. Serial No. 420,269.

To all whom it may concern:

Be it known that I, ALBERT L. FIERLEIN, a citizen of the United States, residing at the city of Batavia, in the county of Kane 5 and State of Illinois, have invented certain new and useful Improvements in Swimming Dolls, of which the following is a specification.

My invention relates to toys and particularly to that class thereof which is intended 10 for use in water, the interest in which attaches to their performance of various evolutions in that medium.

The object thereof is to provide an adjustably weighted doll having limbs so formed and which may be so positioned 15 that the doll may be caused to perform a great variety of movements in accordance with the position in which the limbs are 20 placed when it is plunged into the water.

The principles of my invention are illustrated in the drawings in which Figure 1 shows a vertical transverse section of a doll structure made in accordance therewith. 25 Fig. 2 is a section of the same upon the line 2, 2 of Fig. 1. Fig. 3 is a similar section, the figure being shown in a different position.

Further describing my invention with 30 reference to the drawings in which like characters of reference denote like parts throughout, 1 is the body portion of a doll, 2 is a head securely attached thereto. Arms comprising the upper portions 3, 3 and the 35 forearms 4, 4 are attached to the shoulders by means of the pivots 5, 5 and the two portions of the arms are attached to each other at the elbows by pivots 6, 6. The hands 7, 7 should preferably be broadened as shown to 40 a spatulate form. Legs comprising the upper or thigh portions 8, 8 are attached to the lower portion of the body by pivot bolt 9 and the lower portions of the legs 10, 10 are attached at the knee joints by pivots 11, 11.

45 The frictional hold of the several members on the body and on each other as established by the pivot bolts should be such as to prevent ready displacement of the members and sufficient to hold them in proper relative 50 position in the water as fixed before the figure is committed thereto and adjusting means may be provided as illustrated by the shoulder pivots 5.

The jointed limbs, or the members thereof 55 as desired, should be of greater specific gravity than that of the material comprising the

body and head. This result may be attained by making them of suitable unitary material or by providing them with fixed weights 12, 12, etc., which are inclosed in 60 the several structures themselves or applied thereto in any suitable or convenient form.

The material comprising the body and head of the figure should be of wood, cork or other material of less specific gravity than 65 that of water. An elongated chamber 13 is formed in the body of the figure and extends upwardly into the head. A limited quantity of readily movable weighting material is placed in said chamber or cavity. 70 This is preferably in the form of ordinary lead shot.

The entire aggregate result of the construction described is to produce a structure having a specific gravity slightly less than 75 that of the water in which it is to be used, so that when immersed the whole will float awash at the surface.

When it is desired to make use of the toy the arms and legs will be moved upon the 80 pivot joints in accordance with the action sought. For instance, if the action desired is that of ordinary diving, the limbs may be positioned as shown in Figs. 2 and 3. The figure then being inverted the shot 14 will 85 move to the normally upper end of the chamber 13 and the head will be overweighted. When plunged into the water the figure will be carried to a considerable depth, the path taken being determined largely by the 90 position of the limbs. The guiding action of the latter, particularly of the arms, will cause the figure to describe a curved path until the body of the figure passes the horizontal and the head begins to rise. The 95 movable weighting material 14 will then move to the lower part of the receptacle 13 as shown in Fig. 3. The center of gravity will be changed and the device will rise head foremost in a curved line to the surface, its path being determined by its velocity and the position in which the limbs were originally placed.

By giving certain positions to the limbs 100 relatively to each other, gyrating or turning motions may be given and by differently disposing the limbs, the figure may be caused to display an infinite number of movements as it is plunged into the water and passes therethrough.

I claim:

1. A swimming doll having a body, a plu-

- rality of members adjustable relatively to passing through water, and automatically movable weighting material associated with the body, whereby the center of gravity of the figure is changed whereby the center of gravity is changed by changes of direction in the water.
- 5 changes in the position of the doll figure.
2. A swimming doll having a body, a plurality of members movable relatively to the body, weights in fixed relation to said members whereby the center of gravity of the 10 figure may be changed by changing the position of the members relatively to the body, and movable weighting material associated with the body, whereby said center of gravity is further automatically changed by 15 changing positions of the doll figure.
3. A swimming doll having a body, a plurality of members movable relatively to the body, weights in fixed relation to said members whereby the same may be shifted relatively to each other to fix the center of gravity of said doll, and movable weighting means associated with the body portion whereby the center of gravity will be automatically further shifted by changes in position of the figure when immersed.
- 20 25
4. A swimming doll having a body, a plurality of members adjustable relatively to the body to determine its direction when
5. A swimming doll having a body, and a plurality of arms provided with spatulate members adjustable relatively to said body, whereby the direction of the figure may be controlled when passing through water.
6. A swimming doll having a body, members of relatively greater specific gravity than that of the body jointedly attached thereto, and movable material within the figure to change the center of gravity thereof when the position of the figure is changed.
7. A swimming doll having a body, provided with an elongated tubular receptacle substantially in the longitudinal axis thereof, movable weighting material in said receptacle, and adjustable members attached to said body whereby rotary motion may be given on said axis when the device is moved longitudinally in water.

In witness whereof, I have hereto set my hand at Chicago, Illinois, this 25th day of October, 1920.

ALBERT L. FIERLEIN.
